TRAY

Wilmot H. McCutchen, 2314 Ellsworth St.,
Berkeley, Calif. 94704

Filed May 8, 1972, Ser. No. 251,556

Term of patent 14 years

Int. Cl. D7—99

U.S. Cl. D7—20

FIG. 1

FIG. 3

FIG. 1 is a front elevational view of a tray showing my new design, a portion of the tray wall being broken away for convenience of illustration;

FIG. 2 is a top plan view thereof; and

FIG. 3 is a bottom plan view thereof.

I claim:

The ornamental design for a tray, as shown.
